EGG CARTON AND THE LIKE

Robert P. Bemiss, San Francisco, Calif.

Application July 27, 1936, Serial No. 92,764

2 Claims. (Cl. 229—28)

This invention relates to a carton construction, particularly one useful for the handling of eggs, fruit and the like, and, more particularly, to a novel form of filler for use in a carton.

5 The marketing of eggs in packages is, so far as the supplying of the packages is concerned, a highly competitive and a low profit per unit industry. The character of the cartons is therefore limited by the cost, for, in general, a price 10 of more than \$9.00 per thousand for the complete carton cannot be realized. While some cartons provide fairly satisfactory protection and provide suitable surfaces for display purposes, the typical cartons on the market are generally subject to at least one or more serious objection. Thus, with the self-locking type of carton, it is 15 very difficult to remove the egg, while the receptacles provided for the eggs are uniform in size so that the various egg shapes cannot be adequately cared for. It is well known that eggs 20 are graded according to weight and not according to exterior configuration, and in the same grade of egg one will find short squat eggs as well as long narrow eggs. With an egg filler 25 providing substantially the same cross-sectional area for reception of an egg, the long slim egg will be loosely held and therefore much liable to breakage. Other disadvantages include the difficulty in removing the eggs, as well as the fact 30 that the carton sides and top fit snugly against the egg so that any pressure applied to the carton results in breakage.

It is in general the object of the present invention to provide a carton and a filler therefor 35 which obviate the aforementioned difficulties.

Another object of the present invention is to provide a novel and cheap form of egg carton construction.

Another object of the invention is to provide 40 a package construction utilizing corrugated paper in a novel manner.

The invention includes other objects and features of advantage, some of which, together with the foregoing, will appear hereinafter, wherein 45 the present preferred form of the invention is disclosed.

In the drawing accompanying and forming a part hereof, Figure 1 is a plan view of a filler section ready for assembly.

50 Figure 2 is a perspective of an assembled filler section.

Figure 3 is a side elevation, partly in section, of an assembled filler.

Figure 4 is a partial plan view of a filler.

55 Figure 5 is an end view of a filler in a carton.

Figure 6 is an end view of a filler slightly expanded from a knock-down position in which it can be shipped.

As a material from which the present carton and filler can be manufactured, I can use chip 5 board, straw board or the like, or I can make up the structure out of corrugated paper. This last material is preferred, inasmuch as it is stronger, more resilient, affords more protection to the article packed, and, at the same time, is 10 cheaper.

In proceeding to practice the invention I take a sheet 6 of suitable material, preferably corrugated paper, and make a plurality of spaced longitudinal cuts 7 therein joined by transverse 15 cuts 8 so that the sheet is, in effect, cut in the form of a series of successive H's lying on their sides and providing a plurality of tongues 10. If corrugated paper is used this is first formed in a continuous manner and the cuts thereafter 20 made continuously as the paper comes from the assembly line. After the cuts are made the sheet is scored as at 11, 12 and 13 to provide sides 17, top 19 and bottom 20 between the longitudinal edges 14 and 16 thereof. The sheet is 25 then folded upon itself on the scores 11, 12 and 13 and the edges 14 and 16 suitably secured together as by a pasted strip of paper 21 or a flanged or glued edge. In making up a filler for 30 eggs the sheet 6 can be provided with any desired number of the H cuts. Usually six H cuts are made so that when two of the tubular sleeves, now arranged in a rectangular form, are secured in a side by side relation, a package for a dozen eggs is provided.

I prefer to utilize a central sheet member 22 and to attach the tubular sleeves on opposite sides thereof. This member is utilized preferably not only as a means to join the two sleeves together but also to provide protection for the articles 40 packed. Thus in Figure 5 I have shown the assembled filler as inserted into a carrier or sleeve structure indicated generally by the numeral 23. This sleeve structure can be made up in the form of a tubular sleeve of corrugated paper, the central sheet member 22 engaging the top 24 of the sleeve and the bottom 25, spacing these apart so that an egg positioned therein, for example, is held out of contact with the top and breakage thus avoided, if the boxes are stacked.

As appears in Figures 4 and 5, the central sheet member is preferably provided with a tab 26 which extends over and is suitably secured as by a seal 27 to the side of the carrier 23 when the filler 55 is in position. In this way the contents of the egg

carrier can be certified and the consumer can be sure that if the seal is unbroken the contents have not been tampered with. When the seal is broken, the tab 26 provides a convenient means with which to remove the filler from the carrier.

5 I prefer to use a corrugated paper outer sleeve 23 since this provides double protection to an egg supported in the filler while the egg is maintained out of contact with the top and sides so that 10 breakage is very difficult. The corrugated paper sleeves can be readily made up, the machines for manufacture of this material being well known, and the cost of fabrication and paper being such that the corrugated structure is even cheaper 15 than the structure when made of chip or straw board.

It is to be noted that, as appears in Figure 3, the side of the filler provides adequate surface 20 upon which any suitable advertising medium can be printed. At the same time, the outside of the carton can be printed, at least on three faces thereof, and thus adequate display surface provided, a factor considered by the larger egg whole-salers.

25 The tubular sleeves are attached to the central member 22 without depressing the tongues 10,

each sleeve resting flat against the member 22 after the manner of Figure 6. When it is desired to use the filler, the sleeves are pulled out and one or more of the tongues 10 depressed (Figure 2) to lock the sleeves open and in an egg receiving position. This is a simple manual operation quickly performed.

5 I claim:

1. A carton comprising an outer carrier including a top and bottom, and a filler insertable 10 into said carrier and including a central member normally engaging said top and bottom and a pair of tubular sleeves carried by said member on opposite sides thereof and subdivided into a plurality of article receptacles.

2. A carton comprising an outer carrier sleeve having a top and bottom, and a filler insertable 20 into said carrier and including a central member normally engaging said top and bottom and a pair of tubular sleeves carried by said member on opposite sides thereof and subdivided into a plurality of article receptacles by a plurality of H cuts 25 along a face of each sleeve to provide lips depending into said sleeves to engage the sides thereof and lock the sleeves open.

ROBERT P. BEMISS.
